UNITED STATES PATENT OFFICE

2,373,318

SNOWPLOW

Walter Jonathan Lewin, Southport, England

Application December 20, 1943, Serial No. 515,007
In Great Britain December 14, 1942

1 Claim. (Cl. 37—21)

This invention relates to snow plows for clearing a snow covered track on railroads, highways and other places.

An object of the invention is to provide an improved method of removing snow from a snow covered track where the snow lies deeply thereon, as for example, in a snow-drift.

A further object is to provide a snow plow which, when operating in deep snow of a snow covered track, will so operate as to displace snow reposing at the higher level of said track downwardly to a lower level thereon and within the limits thereof and remove the said displaced snow away from the track along with snow reposing at the said lower level whence it can be more readily dealt with, thus avoiding the necessity for unwieldy and cumbersome mechanism.

A further object is to provide a novel arrangement of separate snow removing means mounted on a single travelling unit for operating at the higher and lower levels of the snow.

A still further object is to provide novel means for conveying snow, on being removed from the track, to a point where it can be deposited into a collecting vehicle at one side of the track.

With these and other objects in view my invention consists in an improved construction, arrangement and combination of parts of a snow plow whereby the above objects will be attained as hereinafter set out and claimed but it is to be understood that changes in details of construction and arrangement of parts may be made so long as they remain within the spirit of my invention.

Referring to the drawings filed herewith—

Fig. 1 is an elevation of one form of snow plow which is mounted on and forms part of a unit adapted to be traversed by any convenient form of propelling vehicle.

Fig. 2 is plan of Fig. 1.

Fig. 3 is a vertical section taken on the line III—III of Fig. 1.

Fig. 4 is a front end view of the snow plow.

Fig. 5 is a detail view of a part of the plow shown in Figs. 1 to 4 and depicting a deflector cowl at the outlet end of the snow delivery chute of the plow.

Fig. 6 is an elevation of a modified construction of snow plow.

In Figs. 1 to 4 inclusive, 10 represents a truck adapted to be traversed by any suitable propelling vehicle along the railroad, said truck carrying, at its rear end, a power unit 11 for operat-

ing the snow removing means fitted to the truck for operation as hereinafter described.

Rigidly fixed to the truck 10 at the front thereof by brackets 12 and a transverse strut 13 is a snow scoop 14 having splayed vertical side walls 15 and a rear wall which, for a distance upwards from the bottom of the scoop, is upright as shown at 16 and for the remainder of its height is forwardly inclined as indicated at 17 to terminate 10 at the open front of the scoop. The front of the scoop is also inclined forwardly and faces towards the direction of traverse of the truck so as to be presented with its open front to the snow when being advanced therewith along a snow covered 15 track. The scoop 14 is of a width designed to give working clearance to the truck as well as being of a height to operate in the snow simultaneously at both high and low levels and, as it cuts its way therethrough, snow is collected by 20 the scoop from the track and, owing to the inclined rear wall 17 of the scoop 14, snow reposing at the higher level is caused to automatically slide down the said inclined wall and be compressed into the snow lying at the lower 25 level.

Located in one corner of the scoop 14, transversely thereof, is a feed worm 18 rotatable on a horizontal axis, the operating spindle 19 of which is mounted at one end 20 in one of the side walls 30 15 of the scoop and at its other end in a bracket 21 secured to the rear wall 17 of the scoop.

Located in the other corner of the scoop 14 and adjacent the feed worm 18 is a rotary snow thrower 22 having snow lifting and throwing 35 blades 23, said thrower being operated by a spindle 24 rotatably mounted in a bearing 25 supported by the rear wall 17 of the scoop 14. The rotary thrower therefore operates on a horizontal axis at right angles to the axis of the feed 40 worm 18.

The rotary thrower operates in a clockwise direction, as viewed in the front elevation of Fig. 4, and in the upward path of their revolution the blades 23 operate in a vertical snow 45 chute 26 incorporated in the construction of the scoop 14 at a corner thereof adjacent the thrower 22. This chute 26 is provided at its upper and outlet end with a deflector cowl 27, shown in Fig. 5, which is secured to the chute by bolts 50 28 in the position shown, that is, facing outwardly at the side of the truck 10.

The feed worm 18 is driven by a chain 29 which is enclosed in a casing 30 and operated from a shaft 31 driven by reduction gear 32 interposed between the said shaft 31 and a power

take-off shaft 33, the latter being driven from the power unit 11.

The rotary thrower 22 is operated by a chain 34 enclosed in a casing 35 and driven from the power take-off shaft 33 by direct drive therefrom through the reduction gear 32.

As the rigidly fixed scoop 14 is forwardly traversed, snow reposing at a higher level than the rotary thrower 22 and feed worm 18 will be caused to slide down thereonto by reason of the inclined wall 17 of the scoop 14 and snow which falls on to the feed worm 18 will be traversed thereby to the said thrower and the blades 23 thereof will throw the said snow, along with snow sliding down the inclined wall 17 of the scoop 14 directly on to the rotary thrower, up into and through the chute 26 and the deflector cowl 27 will direct the snow sideways from the track. Snow reposing at the lower level, that is to say, directly in the path of the thrower 22 and feed worm 18, will therefore be acted upon by said thrower 22 and worm 18 substantially simultaneously with the snow brought down from the higher level and be removed therewith up the chute 26 and out through the deflector cowl 27 away from the track.

It will be seen therefore that the snow scoop 14 gathers snow, within its side walls 15 and inclined wall 17 for subjection to the action of two independent snow removing means operably accommodated in the scoop and comprised of the feed worm 18 and rotary snow thrower 22. Snow which is directed by the scoop on to the feed worm 18 is conveyed thereby to the rotary thrower 22 for the latter to throw it upwardly into and through the chute 26 simultaneously as the said thrower 22 similarly deals with snow directed to it by the scoop 14.

The thrower 22 rotates at a faster rate than the worm 18 so as to adequately deal with the snow.

Fig. 6 also depicts a snow plow as a unit adapted to be suitably propelled but for dealing with snow reposing at a high level, an endless conveyer element 50 is employed.

In this construction, the scoop 14a is of reduced height and open at the top to accommodate location of the conveyer element 50 which is mounted at its lower end in the upper part of the side walls 15a of the scoop 14a by a driven shaft 51.

The conveyer element 50 is of a width to extend across the full width of the scoop except for the necessary clearance for operation and is upwardly and forwardly inclined, its upper end being provided with a shaft 52 supported by a jib frame pivoted to a bracket 53 at each side of the track 10a, the said jib frame being represented diagrammatically by co-axial tie-bars 54 and 55 connected together by a turnbuckle 56 engaging a right hand screw threaded end 57 of the tie-bar 54 and a left hand screw threaded end 58 of the tie-bar 55 whereby the jib frame can be lengthened or shortened so as to lower or raise the point of support for the shaft 52 and thus alter the height of the conveyer element 50.

The conveyer element 50 is provided with an endless chain band 59 carrying flat snow engaging blades 59 disposed at intervals thereon and

extending for the width of the conveyer so that on operation of the chain band 59 the said blades 59 act upon the snow in their downward path and bring it to a lower level.

5 A feed worm 18a and rotary snow thrower 22a are mounted in the scoop 14a similar to the arrangement of Figs. 1 to 4, for dealing with the snow at the said lower level.

The lower shaft 51 of the conveyer element 50 10 is operated by a chain 60 driven from the shaft 31a which is operated from the take-off shaft 33a through the reduction gear 32a similar to the arrangement in Figs. 1 to 4.

The lower shaft 51 of the conveyer element 50 15 is operated by a chain 60 driven from the shaft 31a which is operated from the take-off shaft 33a through the reduction gear 32a similar to the arrangement in Figs. 1 to 4.

20 In operation, as the truck 10a is traversed forwardly into snow, the conveyer element 50 acts 25 upon and conveys snow from a high level downwardly to a lower level within the limit of the track and towards the feed worm 18a and rotary thrower 22a from which lower level the snow is removed from the track by said thrower in a similar manner to that described with reference to Figs. 20 to 4.

25 The snow scoop 14 or 14a constitutes snow collecting means which cuts into snow to clear a width of pathway therein for the truck 10 or 10a and also for vehicles normally using the track and that section of snow which reposes at a high level in the pathway is displaced or removed downwardly, by the inclined wall of the scoop, 30 within the limits of said pathway to join snow reposing at a lower level within the pathway defined by the scoop and with which snow said displaced snow is removed from the scoop and consequently from the pathway by the snow removing means operating within and independently of 35 said scoop.

40 From the foregoing description of snow plow, it will be seen that snow is mechanically removed from a track by an improved method which 45 consists in cutting a defined width of pathway through the snow by displacing snow reposing at a high level downwardly within the limits of said pathway to join snow reposing at a lower level therewithin and removing said displaced snow along with said snow at said lower level from 45 said pathway.

What I claim and desire to secure by Letters Patent is:

50 A snow plow comprising a vehicular unit, a forward snow collecting scoop carried on said unit and adapted to cut a pathway for said unit through the snow, a snow delivery chute located at one side of and open to said scoop, a rotary thrower mounted to rotate on an axis extending longitudinally of the direction of movement of the vehicular unit within the scoop adjacent the chute and occupying a portion of the width of the scoop, said thrower having throwing blades adapted to discharge snow from the portion of 55 the scoop which it occupies through said chute, and a rotary feed worm mounted to rotate on an axis extending transversely of the direction of movement of the vehicular unit within the scoop, said worm occupying the remaining portion of 60 the width of the scoop and being adapted to deliver snow collected by said remaining portion of the scoop laterally to the thrower.

65 WALTER JONATHAN LEWIN.
